To all whom it may concern:

Be it known that I, Karl G. Oehling, a citizen of the United States, residing at Royal Oak, in the county of Oakland and State of Michigan, have invented a new, original, and ornamental Design for a Table, of which the following is a specification, reference being had to the accompanying drawing, forming a part hereof, in which:

Fig. 1 is a front elevational view of a table showing my new design.

Fig. 2 is a side elevational view.

Fig. 3 is a top plan view, and

Fig. 4 is a perspective view thereof.

The dominant features of my design reside in the portions shown in the full lines.

I claim:

The ornamental design for a table, as shown and described.
